W. T. MADDOX.

PERPETUAL CALENDAR.

APPLICATION FILED MAR. 22, 1922.

1,435,248.

Patented Nov. 14, 1922

UNITED STATES PATENT OFFICE.

WILLIAM T. MADDOX, OF ALEXANDRIA, LOUISIANA.

PERPETUAL CALENDAR.

Application filed March 22, 1922. Serial No. 545,867.

To all whom it may concern:

Be it known that I, WILLIAM T. MADDOX, a citizen of the United States, residing at Alexandria, in the parish of Rapides and 5 State of Louisiana, have invented certain new and useful Improvements in Perpetual Calendars, of which the following is a specification, reference being had to the accompanying drawings.

10 This invention relates to calendars, and particularly to what is known as perpetual calendars, and the object of my invention is to provide a calendar which is truly perpetual, that is which is applicable for use 15 for all time.

A further object is to provide a calendar of this character which is very simple, compact, and which requires but simple manipulation in order to set the calendar to indicate the day of the month upon which any 20 particular event will fall or the day of the week upon which any event will fall from the year 1901 to infinity, and which is adapted to be used as a regular calendar for any 25 month of any year.

30 A further object is to provide a perpetual calendar for all time composed of seven one hundred year calendars, making a seven hundred year calendar which, at the expiration of seven hundred years, repeats itself ad infinitum.

My invention is illustrated in the accompanying drawings, wherein:—

35 Figure 1 is a face view of a perpetual calendar constructed in accordance with my invention;

Figure 2 is a face view of the section B of the calendar enlarged.

Referring to these drawings, it will be 40 seen that the calendar is divided by transverse lines 10 into a series of transverse spaces, each transverse space being divided into seven spaces 11 and there being seven of these series of spaces 11. There are thus 45 49 spaces 11 and each space 11 is divided by vertical lines into seven columns 12, these columns registering with each other from top to bottom of the calendar. At the top of the calendar above the seven columns 11 there are seven spaces 13 having therein certain index letters. Reading from the left, I have used the index letters R, D, N, E, L, A, and K. These letters, however, are purely

arbitrary, but selected by me because the same letters reversed in order will approximate the spelling of "calendar." Each vertical column of spaces 11 is separated from the adjacent vertical columns preferably by double lines 14 or other distinctive lines, and each transverse series of spaces is separated from the next adjacent transverse series of spaces by double lines 15 or other obvious lines of separation. At the lower ends of each of the columns 11 there is provided a series of seven spaces 16 which I have indicated as a, b, c, d, e, f and g, containing the names of the months. The space a is for April and July, the space b for October, c for August, d for March and November, e for May, f for June, and g for September and December. The month of January is indicated at the top of both of the spaces a and b, the month of February is indicated across the top of both of the spaces c and d, so that leap years may be read properly upon the calendar, as will be hereafter indicated. The spaces a to g are also numbered 1 to 7 consecutively.

At the extreme left hand margin of the lettered columns R, D, N, E, L, etc., there is 80 a column designated 17 intersected by the lines 15, thus making seven spaces 18. At the head of the lowermost space is indicated the year 1901, at the head of the second space from the bottom the year 2001, at the head of the third space from the bottom 2101, heading the fourth space from the bottom is the number 2201, at the head of the fifth space is 2301, the sixth 2401 and the seventh is 2501. After the expiration of 90 these centuries, 2601 will take its place in the space with 1901 repeating all that had expired before, and so the other century years in the margin should be increased by 700 to take their proper places in the spaces allotted to them and thus make the calendar continuous for all time. Below the numeral 1901 in the lowermost space 18 is the year 2601, the next column above has the year 2701, and so forth up to the uppermost space 18, which has the year 3201, 3301 being in the lowermost space 18, etc., as indicated fully in the drawing. All of the transverse series of spaces 11 and indicated by the letter B, for instance, apply to the years 1901, 2601, 3301, 4001, 4701, 5401, 6101, and such

figures may be continued indefinitely. The space B may contain numbers indicating centuries from 1901 to 15001, the space C may have figures applicable to the year 5 2101 to 17501, the space D from 2501 to 20001, etc. Ordinarily, however, each space will contain but a few year figures.

Though each of the spaces 10 which is divided into seven vertical columns 11 may 10 be completely filled out with year numbers, this is not necessary, and preferably and in order to make the calendar more compact, only one of these spaces 10 is filled out, that is the space on the extreme left hand lower 15 corner of the calendar. The columns 12 of this space are filled in with year numbers and it is not necessary to do more than indicate the last two numbers of the year, as for instance 01, 22, 44, 72, etc. These 20 figures increase in value from the lower end of the column upward and the figures which indicate leap years are indicated in wide-faced type or in type of a distinctive color.

It will be noted that the lowest figures of 25 the several columns in this space 11 at the extreme left hand lower corner of the calendar will be consecutively 01, 02, 03, 09, 04, 05 and 06. Reading across the calendar, the next succeeding space 11 has the figures 06, 30 01, 02, 03, 09, 04 and 05 at the lower end of the respective columns. The next succeeding space or the space above the month of August has the figures 04, 05, 06, 01, 02, 03 and 09 at the base of the columns, etc., the 35 position of the figures from 1 to 9 advancing one space for each month.

Reading upward to the successive spaces 10 above the space 10 at the lower left hand corner of the calendar, it will be seen that 40 in the lower end of the first column of the lowermost space is the numeral 01, in the next space there is the numeral 02, in the next space 03, the next space 09, the next space 04, the next space 05, the next space 45 06, in other words the figures for successive centuries at the feet of the columns 10 are the same as the arrangement of the figures in the seven columns 11 of any single space 10 reading transversely.

50 It will be noted that each transverse series of spaces 10 constitutes a complete century column. Thus, for instance, the first transverse series of spaces or sections B contains calendar numerals which are applicable to the entire century from 1901 to 2001. They are also applicable to the entire century from 2801 to 2701 and to the entire century from 3301 to 3401 and so on. Disposed below the series of columns and the 55 month spaces but located in any suitable position on the calendar is a rectangular space 19 which is divided into 35 spaces by vertical and transverse lines, these spaces being filled with the numbers 1 to 31 of the 60 month. Above this space 19 the material of 65

the calendar is cut to provide two slits 20, and slipping through these slits is a strip 21 having thereon 26 spaces arranged in two horizontal rows. The first series of spaces are lettered with the same letters as are disposed in the spaces 18 and arranged in the same order, these letters being repeated. Below these letters are arranged the abbreviations for the days of the week. These capital letters and abbreviations for the days 75 of the week are duplicated, or nearly so, in order that in manipulating the slip there will always be enough of either of them to cover the little calendar. This strip 21 is adapted to be inserted through the slots 20 80 and shifted longitudinally to bring any particular day of the week or any particular day indicated letter above any of the vertical columns of the monthly calendar 19.

It will be seen that I have used 700 years 85 as a unit. The reason for this is that I have found that 700 is the only number which may be divided by 28 into centuries without a remainder. I use the number 28 for the reason that I have found from another calendar of my manufacture that the calendar repeats itself every 28 years and I divided centuries by 28 until I found that 700 was divisible without a remainder. Inasmuch as there are 30 days in a month and as there 95 are seven days in a week, it is evident that some months must run along with other months a part of the time and with still other months at other times. Therefore, it will be seen that January runs along with April 100 and July in leap years and with October in years that are not leap years. Hence in looking for January in a year that is a leap year, the year will be found in the section 1, and in looking for a date in January 105 where the year is not a leap year, the year will be found in section 2. The same is true with regard to February in sections 3 and 4. Leap year does not affect either April, July or October, nor does it affect August, March 110 or November. Only January and February are affected by the leap years.

It will be obvious that the abbreviations for the days of the week might be disposed at the upper ends of the columns 11 instead 115 of the arbitrary letters so disposed, and it will be seen by reference to the left hand lowest section that the columns 11 correspond to the days of the week and that the sections correspond to the various months, 120 this particular section at the lower left hand corner corresponding to the months of April, July and January of a leap year, and that the year numbers are arranged in these columns in accordance with the day upon which 125 the first day of the months associated with the columns will fall on any particular week day. Thus, for instance, by reference to the first column of the series, it will be seen that the first day of April or July in the years 130

01, 07, 12, 18, 29, 35, 40, 46, etc., and the first of January in the leap years 12, 40, 68 and 96 will come on Monday, and by reference to the second column that the first day of 5 the month for the months of April and July, or January in leap year, will occur on Tuesday for the years 02, 13, 19, 24, 30, 41, and so on. Assuming that all the sections 10 had the year numerals arranged in their columns, it will be obvious that it is a very simple matter to discover what week day the first day of any month of any year will occur. By referring, however, to the bottom numerals on the several columns in the 15 left hand lower section, reference may be easily made to any other section and to the proper column in any other section without the necessity of filling all the other sections with year numerals.

20 A number of examples will indicate the manner in which the calendar is used and its value. If it be desired to set the monthly calendar for the month of February, 1922, find the numeral 22 in the century calendar B, 25 section 1. It will be seen that this numeral 22 is found in the second column from the right hand side. At the lower end of this column will be found the numerals 05. By now looking under the month column February 30 in the section 4 (for the reason that the year 1922 is not a leap year), the numerals 05 will be seen. This numeral 05 comes under the letter N at the top of the calendar. The strip 21 is now shifted until 35 the letter N is brought above the first day of the month in the space 19, and the monthly calendar consisting of the strip 21 having the days of the weeks thereon and the space 19 having the dates of the month thereon 40 will be set for the month of February, 1922. This strip remains set during the month of February and when a change is required, as for instance for the month of March, the same manipulation is made. In other words, 45 the strip is shifted so as to bring the days of the week, as indicated on the strip, into proper relation to the days of the month, as indicated in the space 19. It is obvious that by shifting the strip 21 over the monthly 50 calendar 19 in accordance with the days, that the days of the week in any month or any year from 1901 onward may be indicated.

For instance, if it be desired to set the monthly calendar to show what relation the 55 days of the week will bear to the days of the month for the year 2201 and the month of January, then by reference to the calendar it will be found that the year 01 is not a leap year. Therefore, reference is made to section 60 2 instead of section 1, and referring to the transverse series of columns for the year 2201, it will be seen that 01 (of the second section) occurs beneath the letter A, and if now the strip 21 be shifted so that the letter 65 A is disposed above the first day of the

month in the space 19, then the calendar for January, 2201, will be indicated.

Having seen how the calendar may be manipulated to indicate the relation of the days of the week for any particular month 70 for any particular year, it will be shown how the calendar applies to working out other problems. For instance, suppose it is desired to know what day of the week fell on October 24, 1901. Again reference is made 75 to the section 1, and looking through the section it is found that the year 1901 occurs at the bottom of the first column. Reference is now made to section 2 for October and the reference numeral 01 is found at the lower 80 end of the second column which is headed by the letter D. If now the strip 21 be shifted so as to bring the letter D over the first day of the month, then the monthly calendar will be set for the month of October, 85 1901, and it will be obvious that the 24th fell on Thursday.

If the question be the day of the week upon which Christmas, 1922, will fall, by referring to section 1, 22 will be found in the 90 second column from the right hand end and in the bottom of this column will be found the numerals 05. Referring to section 7 over the heading December and to the column marked 05, it will be seen that this column is headed by the letter L. Setting the strip 21 so that the letter L is over the first 95 of the month, the calendar is set for December 22nd and it will be seen that the 25th will occur on Monday.

If a note for \$150 was drawn payable on June 13, 1926, on what day of the week will it become due? Again referring to the section 1 and looking for the year number 26, this year number is found in the fourth column from the right and at the foot of this column is the year number 09. Looking under the section 6 for the month of June and for the numeral 09, it is found that this numeral is in the second column headed by the 100 letter D, and setting the strip 21 with the letter D above the first day of the month, it will be seen that the 13th will fall on Sunday so that the note cannot be collected.

Let the question be, what will be the third 115 day of the second week in May, 1929? By setting the calendar for May, 1929, it will be seen that Friday, the 10th, is the third day of the second week. Upon what day of the week will the 22nd of February fall in 1940? 120 Looking through section 1 for the numeral 40 it will be found that this numeral is indicated in black-faced type, indicating that it is a leap year. This numeral occurs in the first column of section 1. The number 125 at the lower end of this column is 01. As before remarked, 1940 is a leap year. Therefore, in making reference to the month of February, it will be necessary to look in section 3 and 01 will be found in the fourth 130

space from the left hand end of this section, which is headed by the letter E. Setting the strip 21 so that the letter E is above the first day of the month, it will be seen that 5 February 22, 1940, will fall on Thursday.

- Problems such as the following can be easily worked out by the same principle: What is the next leap year in which January 16th will come on Wednesday, and what is 10 the next year that is not a leap year on which January 16th will fall on the same day? Upon what dates of the month will Tuesdays fall in 1929? What will be the next date when March 4th will come on Sunday? 15 When will be the first Monday after the second Thursday in October, 1922, etc? These problems will indicate the great diversity of questions which will be answered by this calendar.
- 20 It is not necessary to fill every section with numerals, as is the section B, as the numerals at the bottom of each column in a section have exactly the same years in the column with it, and this is all over the 25 calendar. Thus there is no necessity of more than one set of figures, if the bottom figures only were used to take the place of the whole section of figures. It is then possible only to refer to these bottom figures for the year 30 and whatever column these figures are in if it has at its foot a numeral which would indicate by reference to the proper section for the proper year and month the day of the week upon which the first day of the month 35 would fall for that particular period, that is where the century and the month would intersect. Where the year number is no larger than the numerals at the foot of the different columns of years in the section, there 40 is no need to refer to section B but reference can be immediately made to the proper section under the proper year.

While I have indicated a particular form for the calendar and particular style in 45 which it may be printed, obviously I do not wish to be limited to this style or to the particular form. It is obvious that the style and form may be changed in many ways without departing from the spirit of the invention as defined in the appended claims. 50 It is also obvious the paper and printing may be of any colors desired.

I claim:—

1. A calendar including a transversely extending series of sections, each section having associated therewith the name of a month, one of said sections being divided into a series of seven vertical columns containing year numbers for a hundred years, each of said columns being headed by the figure denoting a week day and the year numbers being arranged in said columns in accordance with the day of the week upon which the beginning of the month associated with the column will fall, a complementary monthly calendar having indicated thereon the days of the month from 1 to 31, and a shiftable slip associated with the complementary calendar and having thereon the same week day indicating figures in the same order as are used to head the columns. 55 60 65 70

2. A calendar including a plurality of series of seven transversely extending sections, each series having sections arranged in alignment with the like sections of the next adjacent series and there being seven series of sections, all of the sections in alignment with each other being divided by vertical lines into seven spaces, each space being headed by a figure denoting a week day and each of said sections being associated with the name of a month, each of the transverse series of sections having associated therewith year numerals denoting intervals of 700 years, the year numerals of each transverse series differing from the year numerals of the next succeeding transverse series by intervals of 100 years, one of said sections having in its seven vertical columns year numerals for 100 years, each column having therein the year numerals indicating those years upon which the beginning of the month associated with the column will fall on the week day appropriate to the column, a complementary monthly calendar 95 having indicated thereon the days of the month from 1 to 31, and a shiftable slip associated with the monthly calendar and having thereon the same week day indicating figures in the same order as are used to head the columns. 90 95 100

In testimony whereof I hereunto affix my signature.

WILLIAM T. MADDOX.
